ATTYS.

UNITED STATES PATENT OFFICE.

ELMER M. JONES, OF ATLANTA, GEORGIA, ASSIGNOR TO JONES SIGNAL SYSTEM COMPANY, OF ATLANTA, GEORGIA, A CORPORATION OF GEORGIA.

ELECTROMAGNETIC DEVICE.

1,109,678.

Specification of Letters Patent. Patented Sept. 8, 1914.

Application filed November 7, 1907. Serial No. 401,057.

To all whom it may concern:

Be it known that I, ELMER M. JONES, a citizen of the United States, residing at Atlanta, in the county of Fulton and State of Georgia, have invented a certain new and useful Improvement in Electromagnetic Devices, of which the following is a full, clear, and exact description, reference being had to the accompanying drawings.

10 This invention relates to electromagnetic relays; it is especially well adapted for relay mechanism for operating signals on cars or locomotives, the signal being actuated as the vehicle engages a suitable contact member along the track. Such system is shown, described and claimed in my application No. 357,364, filed February 14, 1907.

One of the objects of this invention is to provide for signaling mechanism (and particularly mechanism of the type indicated) a reliable relay for controlling and operating such mechanism. This relay is adapted to be operated upon the closing of an electrical circuit in the manner above indicated; 25 its operation is extremely rapid, and, after the momentary closing of the circuit by such relay, to operate the signal, means are provided for holding the parts in indicating position until such time as the signal may be 30 replaced.

I have found that my relay is unaffected by the jarring of the traveling vehicle, but that, upon the closing of a circuit for a very small fraction of a second, it will operate 35 with certainty.

One of the advantages of my relay is that it reduces to a minimum the time required for the initial closing of the relay circuit and hence reduces the length of the contact 40 member which the traveling vehicle or the contacts carried thereby engage.

The invention comprises an arrangement of magnets and armature whereby the operation above described may be realized.

45 More particularly, it includes the peculiar construction of the relay and the arrangement of the circuits.

The invention may be defined as consisting of the combinations of elements embodied in the claims hereto annexed and described in the drawings forming part hereof, wherein—

Figure 1 represents a plan view of a signaling device constructed in accordance with 50 my invention, the top plate of the casing be-

ing removed; and Fig. 2 represents an end elevation of the same, the casing being shown in section.

Describing the parts by reference characters, 1 denotes a suitable base having mounted thereon a stud 2 to the outer end of which there is pivoted a signal device 3, said device being shown as a disk carried by the arm 4 by which it is pivoted to said stud.

5 5 denotes a fixed disk of white which is arranged behind a transparent portion 6 of the cover 7, the disk 3 being of some color different from that of disk 5, as red.

8 denotes a magnet supported from base 1, said magnet having a pair of reversely wound coils provided with a common core 9. Opposed to magnet 8 and spaced therefrom is a second magnet 10 having a core 11.

12 denotes an armature which is pivoted to a stud 13 carried by the base, said armature being provided with an integral operating and circuit-closing member 14, projecting at an angle therefrom. Armature 12 is provided with a soft iron head 15 and a double contact member 16 adapted to engage 75 oppositely-arranged contact screws 17 and 18.

19 denotes a spring which is secured to the lower surface of arm 14, the upper end being adjustably engaged by a screw 20 mounted in a post 21. Arm 14 is provided near the outer extremity thereof with a spring 22, for a purpose to be described hereinafter, and the armature proper 12 is provided with a lateral lug 23 which is adapted to engage 80 the lower end of an arm 24, which is rigid with the arm 4 of the signaling device.

25 denotes a lever pivoted to a stud 26 and having its upper end projecting upwardly in proximity to adjusting screw 20 and having connected thereto a spring 27. Lever 25 is provided with an operating arm 28 adapted to be brought into engagement with push pin 29 by means of spring 27 and with a downwardly-projecting lug 28a.

30 and 31 denote two series of batteries. Opposite terminals of battery series 30 are connected respectively with binding posts 32 and 33. The opposite terminals of battery series 31 are connected respectively with binding posts 33 and 34. From binding post 32, wire 35 leads to one end of winding 36 of magnet 8, and wire 37 leads from the other end of said winding to binding post 33.

38 and 39 denote the line wires which lead 110

to the external or track circuit-closer. These line wires are connected respectively with binding posts 40 and 41 and said posts are in turn connected respectively with wires 42 5 and 43. From wire 35 there leads a wire 44 which is connected in parallel with windings 36^a and 46 on magnets 8 and 10 respectively. The opposite ends of the windings 36^a and 46 are connected with wire 43 by 10 means of wires 47 and 47^a respectively. Binding post 34 is connected to the same wire 42 as binding post 40, and 42 is connected to arm 14. Below arm 14 there is arranged the stop and contact screw 48, said 15 contact screw being also connected to wire 47^a.

With the parts arranged as described, the operation will be as follows: Normally current flows from battery series 30 through 20 winding 36, thereby energizing the magnet and retaining the armature 12 in the position shown in full lines in the drawing. Suppose that the circuit between the ends of the line wires 38 and 39 is closed, as by 25 the vehicle traversing a portion of track suitably equipped with a circuit-closing device. This makes a short circuit through the line wires 38 and 39, and the voltage of the combined battery series flows momen- 30 tarily through the relay comprising windings 36^a and 46. The current flowing through winding 36^a neutralizes the action of winding 36, and current flowing through winding 46 strongly energizes electro-magnet 10, drawing the armature downwardly until spring 22 engages contact 48. As soon as contact is made between 22 and 48, another short circuit is established which takes the place of that made through wires 38 40 and 39 and holds the armature firmly in its new position. This circuit is made through wires 35 and 44, windings 36^a and 46, wires 47 and 47^a to contact 48, through spring 22, arm 14 and wire 42 and binding post 34 45 back to battery 31. The movement of armature 12 downwardly releases arm 24 from engagement with lug 23 and the signal disk 3 drops by gravity to the position of the disk 5, arm 4 engaging stud 49, this action 50 being facilitated by spring 50. To return the armature to its normal position, the re-setting rod 29 is pushed into engagement with arm 28, rocking lever 25 on its pivot and forcing arm 24 upwardly. As lever 25 55 moves upwardly, the inwardly projecting lug 28^a engages arm 14 and moves the armature upwardly, at the same time breaking the circuit through windings 36^a and 46. The circuit which includes winding 36 per- 60 sists, and the armature will be held in position by the magnet 8 energized by this circuit, and lug 23 supports the signal 3 in elevated position as before. Arm 25 serves not only to reset the signaling device 3, by 65 engaging the arm 24, but also, by means of

lug 28^a, engages the arm 14 projecting from armature 12 to thereby reset said armature. It will be observed from Fig. 1 that there will be considerable lost motion of arm 25 before lug 28^a engages 14. This enables 70 arm 24 to be elevated a sufficient distance to clear the supporting lug 23 and allow the latter to be swung up into engaging position by the operation of lug 28^a.

The arrangement of magnets, armature 75 and circuits described provides a very effective and reliable relay and while it is well adapted for use in connection with signaling mechanism, I do not intend to be limited to such use except as such limitation may be included in the claims hereto annexed.

Having described my invention, I claim:

1. In an electro-magnetic device, the combination of an armature, a pair of electro-magnets therefor, one of said magnets having two coils, a circuit including one of the coils of the last mentioned magnet, a circuit including the other coil of said magnet and the coil of the other magnet, means for momentarily closing the second circuit, and 85 means for thereafter maintaining closed a third circuit including the two last-mentioned coils, substantially as specified.

2. In an electro-magnetic device, the combination of an armature, a pair of electro-magnets therefor, one of said magnets having reversely acting coils, a circuit including one of the coils of the last mentioned magnet, two circuits including the other coil of said magnet and the coil of the other 100 magnet, means for momentarily closing one of the last mentioned circuits, and means operable by the movement of the armature for closing the other of the two last-mentioned circuits, substantially as specified.

3. In an electro-magnetic device, the combination of an armature, a pair of opposed electro-magnets therefor, one of said magnets having reversely acting coils, a closed circuit including one of the coils of one of said magnets, two circuits including the other coil of said magnet and the coil of the other magnet, means for momentarily closing one of the two last-mentioned circuits, and means, operable by the movement of the armature by the momentarily-closed circuit, for closing the other of the last-mentioned circuits, substantially as specified.

4. In an electro-magnetic device, the combination of an armature, a pair of electro-magnets therefor, one of said magnets having reversely acting coils, a circuit including one of the coils of one of said magnets, two circuits including the other coil of said magnet and the coil of the other magnet, one of the last-mentioned circuits including a pair of line-wires adapted to be momentarily cross-connected, and means, operable by the movement of the armature by the momentarily-closed circuit, for closing the other 120 125 130

of the last-mentioned circuits, substantially as specified.

5. The combination of an armature, a magnet having thereon opposed windings, 5 an electrical circuit for transmitting current through one of said windings thereby attracting said armature, an electrical circuit for transmitting current through the other winding to thereby deenergize the magnet 10 and release the armature allowing it to move, a second electrical circuit through said last mentioned winding closed by the movement of the armature, and means for concurrently replacing the armature and 15 breaking the circuit through the latter winding, substantially as specified.

6. The combination of an armature, a magnet arranged to hold said armature in one position, said magnet having thereon 20 opposed windings, an electrical circuit including one of said windings, a second magnet adapted to operate the armature in the reverse direction, a circuit adapted, when closed, to transmit current through the 25 winding of the second magnet and through the second winding of the first magnet, and a circuit for maintaining the flow of current through said windings after the breaking of the other circuit mentioned, substantially as 30 specified.

7. In an electro-magnetic device, the combination of an armature, a pair of electro-magnets therefor adapted to operate the same in reverse directions, one of said magnets having thereon opposed windings, an 35 electrical circuit through one of said windings for normally energizing the magnet, a second circuit including the winding of the second magnet and the other winding of the 40 former magnet arranged to deenergize the

former magnet, said circuit arranged to be closed by an external circuit-closer, and a third circuit including the armature the winding of the second magnet and the second named winding of the first magnet to 45 deenergize this magnet, substantially as specified.

8. The combination of an armature, a pair of electro-magnets adapted to operate the same in reverse directions, one of said magnets having thereon opposed windings, a circuit including one of said windings for holding the armature, a second circuit including the other of said windings to deenergize this magnet and including the 50 winding of the second magnet, a closer for the second circuit, and means for resetting the armature and thereby simultaneously breaking the second circuit and reenergizing the first magnet, substantially as specified. 55

9. The combination of a pair of opposed magnets, an armature movable therebetween, one of said magnets having opposed windings, a circuit including one of said windings, a second circuit including the other of 60 said windings to deenergize the magnet and including the winding of the other magnet, an arm projecting from said armature and arranged to close said second circuit, and means for simultaneously restoring the 65 armature to normal position breaking the second circuit and reenergizing the first magnet, substantially as specified.

In testimony whereof, I hereunto affix my signature in the presence of two witnesses. 70
